SUPPORTING ROCKER FRAME
Gary D. Cooper, Randolph, Mass.
(508 Fountain St., New Haven, Conn.)
Filed Jan. 29, 1963, Ser. No. 254,697
4 Claims. (Cl. 5—105)

My invention relates to a rocker frame for receiving and supporting the removable crib or lift-out portion of a baby carriage or perambulator. More particularly, my invention provides an oscillatory supporting frame for receiving the removable basket-like bed portion of a baby carriage whereby this portion of the carriage is converted into a cradle with rockers thereon.

In recent years, manufacturers of baby carriages or perambulators have offered models of their vehicles in which the crib or bassinet body portion constituting the bed for an infant occupant is readily removable from the wheeled frame forming the rest of the vehicle. When removed from the carriage frame, this basket-like body, called a "lift-out," is self supporting so that it may be placed on the ground, the floor, a table, in a car, or on any horizontal supporting surface to serve as a stationary bed for the infant. Unfortunately, when placed directly on a supporting surface, the bottom of the lift-out may come in contact with surfaces which are cold or sometimes wet or dirty, with resulting discomfort to a baby in the bed and possible damage to the basket-like body.

One object of my invention is to provide a supporting structure or framework for receiving a lift-out bassinet or bed and for holding it supported somewhat above a surface on which it may be placed so that the bottom of the bassinet does not come in direct contact with the supporting surface and space is left for air circulation and ventilation below the body of the bed. A coincident object is to provide such a supporting framework with curved surfaces forming rockers so that, when the bassinet lift-out is in or on the framework, a cradle will be provided for the infant.

Another object of my invention is to provide a rocker type supporting frame for a removable baby carriage body that is extremely stable and is provided with means to resist being tipped over.

A further object of my invention is to provide a supporting rocker frame of the character described that is inexpensive to make, light in weight and simple in construction.

A still further object of my invention is to provide such a bassinet-supporting rocker frame adapted to receive and hold lift-outs or carriage bodies of various lengths and depths without adjustment and that will accommodate a limited range of lift-out widths with a certain amount of adjustment.

In carrying out the objects of my invention, in one embodiment thereof, I provide an open frame comprising a pair of mutually facing generally parallel upright U-shaped end portions held in spaced apart relation from each other by a pair of horizontal parallel spacing side bar portions, each extending between and joining the facing upright arm of one side of each U-shaped portion. Each U-shaped end portion is dimensioned to receive, between its vertical side arms and above the bight of the U, the bottom and part of the sides of the body of a lift-out bed or bassinet, the bottom of the bassinet body being held above the bottom of the bight of the U by the start of the inward curvature of the bight or additionally by side support projections added at these locations. This provides spacing of the bottom of the bassinet or bed from the floor or other supporting surface on which the frame is placed. If the frame

2

is made of pliable or bendable material, as is preferred, minor adjustments in width of the frame may be made to accommodate, to a limited extent, variations in width of beds or bassinets simply by pulling the spacing bar portions away from each other or pushing them toward one another to suit the size in width of bed body being used. The horizontal length of the spacing bars joining the U-shaped portions is preferably shorter than the length of the smallest bed body expected to be supported, the ends of the bed body lift-out therefore always extending outwardly beyond the U-shaped portions, as will be shown. The height of the straight sides of the U-shaped portions, which determines the height of the side spacing bars, is preferably not great enough to put these bars above the top edge of a bed or bassinet carried by the frame. The curved bottoms of the U-portions provide a rocker surface which adapts the frame to serve as a cradle, which can be rocked in the manner of such devices. To prevent over-rocking, projecting bumpers are added to each side of each U-portion near the ends of the curved portions of the U so that if the cradle frame is tilted too far, the bumpers will strike the supporting surface upon which the frame is placed and prevent further rocking or upset in that direction.

Other objects and further details of that which is believed to be novel and included in my invention will be clear from the following description and claims, taken with the accompanying drawing in which is illustrated 30 a preferred example of a supporting rocker frame embodying the present invention and incorporating features outlined above.

In the drawings:

FIG. 1 is a perspective view of an exemplary supporting rocker frame according to my invention;

FIG. 2 is an exploded side elevational view of the frame of FIG. 1 in conjunction with a typical basket-like lift-out bed which may be used therewith;

FIG. 3 is an end view of the frame showing a typical bed body lift-out in position therein.

FIG. 4 is a greatly enlarged end view of one segment of the rocker frame showing some details of construction, and

FIG. 5 is an enlarged end view like FIG. 4 but showing a variation of a detail for supporting the bottom of a lift-out in the frame.

For convenience in portability, storage and wider use of the equipment, it is customary for many makes or styles of baby carriages to be provided with a bed body lift-out 10 of generally rectangular basket-like form, this body portion being readily removable from the wheeled frame portion of the carriage to serve as a self-supporting but collapsible crib or bassinet. One such typical lift-out includes a rectangular rigid upper frame 12, which may be padded if desired, this frame carrying depending mutually joined end walls 14 and side walls 16 made of waterproof flexible fabric or similar material. A bottom 18, of like material, may be secured to or on a relatively stiff bottom supporting board 19 at the lower extremities of the depending end walls and side walls. The bed body may have a pair of U-shaped stiffening members 15 pivoted at their ends to the frame 12 as at 17. To allow collapse of the flexible ends and sides, the stiffening members are swung up into the same plane as the upper lift-out frame.

When it is desired to use the assembly as a self supporting crib or bed, the U-shaped stiffening members 15 are swung downwardly against the bottom 18 with its stiffening board 19, placing the end and side walls under tension and holding the upper frame 12 above the bottom board 19.

Removable basket-like beds or lift-outs of other styles or designs are provided for various different models of baby carriages, but many are made of an outside width close to 15 inches, a depth of about 10 inches or more and a length of about 30 inches or more. Although such beds having depths and/or lengths several inches greater than these are known, it is relatively seldom that their width departs much from the 15 inches given, perhaps because of an attempt at standardization, based upon the maximum size of an infant expected to use the crib. The structure of the typical lift-out or bed just described therefore is not per se a part of my invention, although the common dimensional and self-supporting characteristics of such basket-like bodies are used to advantage in a rocker frame for such beds according to this invention.

In a preferred embodiment of my invention I provide a framework open at its ends and top and made of hollow aluminum tubing. In the best form known to me, I use two equal lengths or $\frac{3}{4}$ " diameter aluminum tubing, identically formed and then joined together. Each member includes a central curved rocker portion 20 forming the bottom of a U, with upright or vertically directed end portions 22 at the ends of the rockers and horizontally directed side portions 24 extending from the end portions 22. Well-known methods and equipment may be used to shape the frame members in this fashion. The ends 26 of each tubular member of the frame are joined in aligned and abutting relationship to corresponding and opposite ends of the other frame element so that together the horizontally extending side portions 24 of each frame member constitute a pair of parallel spaced side portions or bars for the completed frame. The ends of each of the frame members may be joined together by an internal plug or core and cooperating rivets, as shown, or they may be welded, brazed, or otherwise suitably secured together. In effect, the completed frame is a single closed loop structure shaped as above described.

As seen most clearly in FIG. 1 of the drawing, the closed loop frame thus comprises a pair of mutually facing, generally parallel upright U-shaped end portions 20 and 22 held in spaced apart relation from each other by a pair of horizontal parallel spacing bar side portions 24, extending between and joining the facing upright arms 22 of the U-shaped portions. The clear space between the upright arms 22 at each end is preferably approximately 15 inches so that the standard width of a typical lift-out bed may be accommodated readily. However, if the particular bed being received within the frame is somewhat below or above this width, the aluminum tubing of which the frame is made is sufficiently pliable that the sides of the frame may be slightly pushed together or pulled apart and bent, as shown in FIG. 3 by the dotted lines, to take care of a limited range of widths of a bed.

The length of a frame according to a preferred form of the invention is about 27 $\frac{1}{2}$ inches, so that this frame will take care of cribs or beds having lengths in excess of this dimension by several inches without producing an unstable assembly.

As far as the depth of the frame is concerned, the dimension of the upright portions 22 from the level of the horizontally extending side portions 24 to the beginning of the curvature of the rocker portions 20 is preferably about 8 inches. This will take care of carriage lift-out beds having at least that dimension from the bottom to the top of the basket-like body. As in the case of bed bodies having a greater length than the preferred length of my frame, beds having a greater depth than the one selected will simply project further beyond the frame.

Whatever its depth, the bottom of the bed body will be supported at each end between the upright end portions 22 of the frame, the start of the curved portion 20 on each side furnishing this support. If desired, and to provide a more stable support at that point in addition to the curvature of the frame, a bolt or rivet 28 may be extended through the frame, provided with a projecting

nut or head 30 on the inside of the frame to serve as a definite support. In FIG. 4 one corner of the bottom of the bed body is indicated by broken lines to show its position against the inwardly projecting support 30. In the form of FIG. 5 a modified form of bolt or rivet 29 is shown with an extended projection 31 thereon to support the bottom of a bed having considerably narrower width than the standard 15 inches.

As will be seen from the drawings and the explanation above, this supporting frame, by its curved ends 20, provides a rocker support for a baby's bed or crib lift-out, the rockers supporting the bottom of the bed above a supporting surface for proper ventilation. This converts the crib or bed into a convenient cradle, useful in the time-honored manner of all such devices. However, for safety's sake, it is desired to limit the amount of oscillation or rocking motion that may be obtained with this cradle. Therefore, I have provided, near the ends of each central curved portion 20 of the frame, a resilient bumper or rocker stop 32 (which may be made of rubber or other suitable resilient material) held in place on the frame as by a machine screw 34 or in any other suitable fashion. By its projection outwardly of the frame, each bumper 32 will prevent the rocker from being tipped beyond the limit of motion determined by the location of the bumper, and the resilient nature of these elements will not only prevent sharp jarring of the cradle when it is rocked but also will prevent possible marring of the surface on which the cradle is placed and rocked.

As will be evident from the foregoing description, certain aspects of this invention are not limited to the particular details set forth as an example, and it is contemplated that various and other modifications and applications of the invention will occur to those skilled in the art. It is therefore intended that the appended claims shall cover such modifications and applications as do not depart from the true spirit and scope of the invention.

What I claim as new and desire to be secured by Letters Patent of the United States is:

1. A supporting rocker frame for receiving and removably holding therein a basket-like bed unit of the type having a horizontal bottom and upwardly extending ends and sides, said frame consisting of a single closed-loop structure open at its top and ends and including only a pair of identical symmetrical spaced upright U-shaped end portions each having a curved bottom and vertical straight sides and a pair of identical horizontal parallel side bar portions extending between and joining the upper ends of the vertical sides of said U-shaped portions to hold said end portions in spaced apart relation, facing and parallel to each other, the curved bottoms of said U-shaped end portions serving as rocker surfaces for supporting the closed-loop frame structure, the horizontal bottom of a basket-like bed being received and removably held between the vertical sides of said U-shaped portions above said rocker surfaces and the sides of the bed being held between said horizontal side bar portions.

2. A supporting rocker frame as claimed in claim 1 including inwardly extending projections adjacent the junction of the curved bottom and vertical sides of said U-shaped end portions, removably to engage and support the horizontal bottom of a bed in said frame above said rocker surfaces.

3. A supporting rocker frame as claimed in claim 1 including outwardly extending bumper projections near each end of the curved bottom of each said U-shaped portion, permitting rocking but preventing over-rocking of said frame by serving as stops.

4. A supporting rocker frame for receiving and removably holding therein a basket-like bed unit having a substantially rectangular horizontal bottom and upwardly

extending ends and sides, said frame consisting of a plurality of elongated pliable tubular members joined together and formed into a single closed-loop structure including only

a pair of identical spaced upright U-shaped end portions 5
each having a curved bottom and vertical parallel spaced sides and

a pair of identical parallel straight side bar portions extending between and joining the upper ends of the vertical sides of said U-shaped portions to hold said 10
end portions in spaced apart relation, parallel to each other, completing a frame open at its top and ends by having spaced parallel upright U-shaped ends joined by the parallel straight side bars

an inwardly extending projection on the inside of said 15
frame adjacent each junction of a curved bottom and vertical side of said U-shaped portions, adapted to engage and support the rectangular bottom of a basket-like bed in the said frame and

outwardly extending resilient bumper projections on the 20
outside of said frame near each end of the curved bottom of each said U-shaped portion, permitting rocking but preventing over-rocking of said frame and serving as cushion stops,

the curved bottoms of said U-shaped end portions serving as rocker surfaces for supporting the total frame structure, the rectangular bottom of a basket-like bed being received and removably held between the vertical sides of said U-shaped portions on said inwardly extending projections above said rocker surfaces with the sides of the bed held between said parallel straight side bar portions, the pliable nature of said tubular frame members permitting bending adjustment of the vertical sides of said U-shaped end portions of the frame toward and away from each other to accommodate beds of different widths.
